DESIGN FOR A RIND STRIPPER

Carl H. Marquardt and Earnest A. Countryman,
Long Beach, and Linnaeus S. Newton, Lyn-
wood, Calif.

Application February 2, 1934, Serial No. 50,602

Term of patent 7 years

To all whom it may concern:

Be it known that we, CARL H. MARQUARDT,
EARNEST A. COUNTRYMAN, and LINNAEUS S. NEW-
TON, citizens of the United States, the first two
being residents of Long Beach, and the third, a
resident of Lynwood, in the county of Los Angeles
and State of California, have invented a new,
original, and ornamental Design for a Rind Strip-
per, of which the following is a specification; ref-
erence being had to the accompanying drawing,
forming a part thereof:

Figure 1 is a plan view of our stripper, showing
the new design.

Figure 2 is a side elevation of the same.

The dominant feature of the design is the ap-
pearance of the jaw element.

We claim:

The ornamental design for a rind stripper, as
shown, and described.

CARL H. MARQUARDT.
EARNEST A. COUNTRYMAN.
LINNAEUS S. NEWTON.
